UNITED STATES PATENT OFFICE.

FREDERICK J. BACON AND DAVID L. DAY, OF GROTON, CONNECTICUT.

BANJO.

Application filed November 23, 1923. Serial No. 676,572.

This invention relates to improvements in stringed musical instruments and more particularly to an improvement in the resonance boxes of banjos, although the invention is not restricted to this particular type of stringed musical instruments.

The resonance box of the ordinary banjo is open at its back and as a consequence the sound waves are directed against the clothing of the player of the instrument and are somewhat deadened or muffled thus greatly detracting from the quality of the tone. It has been proposed to provide a resonant back for the resonance box of the instrument and to form openings in the wall of the rim of the resonance box, the object being to not only enhance the tonal qualities of the sound waves but also prolong their propagation. While such a construction is efficient, the present invention has in view the provision of means whereby the desired results are obtained in a more effective manner thereby enhancing the tonal qualities to a much greater degree than in structures such as referred to.

Briefly, the present invention contemplates the provision of an auxiliary resonance chamber through which the sound waves must pass before emerging from the resonance box so that their propagation is greatly prolonged and their tonal qualities greatly improved.

Another object of the invention is to provide an improved construction of the rim of the resonance box at the margin over which the membrane comprising the head of the resonance box is stretched whereby the rim will be materially reinforced at this portion and a more even tensioning of the membrane obtained.

Other features and objects of the invention will be made apparent as the description proceeds.

In the accompanying drawings:

Figure 1 is a perspective view of a banjo embodying the invention;

Figure 2 is a detail sectional view through the rim of the resonance box of the instrument;

Figure 3 is a detail section showing means for securing the attachment to a banjo.

In the drawings, the resonance box of the banjo is indicated in general by the numeral 1, and the same comprises a rim 2 which is of wood and of the usual annular form, this rim being supported by the neck of the in-

strument which is indicated by the numeral 3. The rim 2 of the resonance box is formed in its inner side at the front of the box with a recess 4 which extends circumferentially of the wall of the said rim, and, rearwardly of the recess, the said inner surface of the rim is formed with a relatively shallow rabbet indicated by the numeral 5, a similar but wider rabbet 6 being formed in the outer surface of the said rim. The numeral 7 indicates in general a member which is fitted onto the forward side of the rim and which comprises outer and inner walls indicated by the numerals 8 and 9 respectively, and a connecting wall portion 10 which is arcuate in cross section, the wall 8 being of cylindrical form, and the wall 9 of frusto-conical form and diverging from the wall 8 rearwardly from the connecting wall portion 10. The wall 9 has its inner marginal portion of cylindrical form and concentric to the opposing portion of the said wall 8, and the wall 8 is seated in the rabbet 6, while the edge portion of the wall 9 is seated in the rabbet 5, as clearly shown in Figure 2 of the drawings, the walls 8 and 9 and connecting portion 10 straddling the forward portion of the rim 2 and the said portion 10 enclosing an annular reinforcing ring 11 which is seated against the forward edge of the rim 2 and confined by the connecting portion 10 of the said member 7. The head of the resonance box is indicated by the numeral 12 and the same is formed from calfskin or any other membrane found suitable for the purpose and at its peripheral portion is stretched over the connecting portion 10 of the member 7 and tensioned and secured in place by the usual clamp rim 13, which rim is tensioned by the tensioning hooks 140 which are of the usual construction and hence require no specific description.

It will now be evident that due to the peculiar form given the inner wall 9 of the member 7, this wall is spaced from the opposing wall of the recess 4 in the rim 2 so that a resonance chamber 14 is provided in the resonance box extending circumferentially thereof at the forward side of the said box. Openings 15 are formed at suitable intervals in the portion of the wall 9 which is seated in the rabbet 5, and preferably the material of the said wall surrounding these openings is stamped in a manner to imitate eyelet rivets. The rim 2 is formed with openings 16 which may be located directly

opposite the openings 15 or in staggered relation thereto, and the outer wall 8 of the member 7 is likewise formed with an annular series of openings 17 which substantially register with the outer ends of the openings 16.

The resonance box of the instrument is closed at its rear by a resonant back which is indicated in general by the numeral 18, and the said back comprises a circular shell or disk of wood or other material found suitable for the purpose which is gradually decreased in thickness or thinned from its periphery toward its middle and has its periphery rabbeted as indicated by the numeral 19. A rim 20 of sheet metal has one of its marginal portions fitted to the rabbeted periphery 19 of the back 18 and secured thereto by screws or other suitable fastening means indicated by the numeral 21. The rim 20 is of substantially bell-shape and its other peripheral portion, which is indicated by the numeral 22, is of less diameter than the peripheral portion which is seated in the rabbet 19. The said peripheral portion 22 of the rim 20 is seated in a rabbet 23 formed circumferentially in the outer side of the rim 2, and securing screws 24 are threaded through bosses 25 at suitable intervals upon the peripheral portion 22 of the rim 20 and engage in sockets 26 in the said rim 2, and these screws constitute means for removably securing the rim 20 to the rim 2 and consequently serve as means for holding the back 18 in proper position with relation to the rear side of the resonance box. Owing to the bell form given the rim 20, the rim will flare outwardly with respect to the rear side of the rim 2, and the peripheral portion of the resonant back 18 will be supported in spaced relation to the rear edge of the said rim 2. The rim 20 is formed in its portion intermediate between its front and rear edges with an annular series of openings 27, and, if desired, eyelets 28 may be riveted in these openings so as to enhance the appearance of this portion of the instrument, or it may be found preferable to so stamp or otherwise form the material of the rim at points surrounding the opening 27, with raised portions in imitation of eyelets.

Where the term "front", or a similar term, is employed in this specification and in the claims, it is intended to designate the side of the body or resonance box to which the membranous head is secured, while the term "back", or the like, refers to that side of the resonance box or body which is open in banjos of ordinary construction.

Having thus described the invention, what is claimed as new is:

1. A stringed musical instrument having a resonance box including a continuous rigid rim and a membranous head, the rim being

recessed in its inner side circumferentially at its front edge, a metallic ring disposed against the front edge of the rim, an annular member disposed to straddle the front edge of the rim and the ring and having an outer wall extending about the front portion of the rim and an inner wall confronting and extending over the recessed portion of the rim to define a resonance chamber disposed within the thickness of the rim, the membranous head extending over the portion of the said annular member which straddles the ring, and means tensioning the said membranous head, the forward portion of the rim and the inner wall of the said annular member being provided with openings for the escape of sound waves produced within the resonance box.

2. A stringed musical instrument having a resonance box including a rim and a membranous head stretched over the forward side thereof, a second rim fitted to and circumferentially surrounding the rear side of the first mentioned rim and flared outwardly and rearwardly with relation thereto, and a resonant back peripherally surrounded by the second mentioned rim and supported thereby in spaced relation to the rear side of the first mentioned rim, the said second-mentioned rim having a circumferential series of openings for the escape of sound waves, and removable means positively securing the said second-mentioned rim to the first mentioned rim.

3. A stringed musical instrument having a resonance box including a rim and a membranous head stretched over the forward side thereof, a wall associated with the rim at the forward side thereof, the rim and the wall forming an auxiliary resonance chamber having axially aligned radial passages for the escape of sound waves produced within the resonance box, a resonant back for the said box, and a second rim circumferentially surrounding the rear side of the rim of the box and flared outwardly and rearwardly with relation thereto and supporting the said resonant back, the said second mentioned rim having openings therein for the escape of sound waves produced within the resonance box and being positively secured at its inner forward periphery to the rim of the box.

4. A resonant amplifying attachment for banjos comprising a resonant disk, a continuous annular rim encircling the disk and of a diameter to receive and constitute a seat for the rear edge portion of the wall of the resonance box of the banjo, the said rim being provided outwardly beyond the banjo resonance box, with sound wave exit openings, and means for positively attaching the rim to the banjo resonance box.

5. A resonant amplifying attachment for banjos comprising a continuous annular

resonant wall having a portion spaced inwardly from its outer periphery and of a diameter to snugly receive and constitute a seat for the rear edge portion of the resonance box of the banjo, the said attachment further comprising a resonant head encompassed and supported by the outer periphery of the said wall, the wall between its said portion and its outer periphery being provided with sound wave exit openings, and means for positively securing the resonant wall directly to the banjo resonance box.

6. The combination with a banjo including the usual resonance box having the usual annular wall, of a resonant amplifying attachment comprising a resonant head of circular form and of greater diameter than the external diameter of the banjo resonance box,

the said amplifying attachment also comprising a resonant wall having its outer peripheral portion surrounding and united to the periphery of the said resonant head and from its said peripheral portion being extended inwardly and forwardly to the outer side of the resonance box of the banjo and snugly surrounding the same, the said resonant wall having sound wave exit openings between its inner and outer peripheries, and means for positively connecting the said resonant wall with the resonance box of the banjo.

In testimony whereof we affix our signatures.
